A. M. MESTON.

SKIRT MARKER.

APPLICATION FILED FEB. 2, 1909.

926,276.

Patented June 29, 1909.

UNITED STATES PATENT OFFICE.

ALEXANDER M. MESTON, OF ROSEVILLE, CALIFORNIA.

SKIRT-MARKER.

No. 926,276.

Specification of Letters Patent.

Patented June 29, 1909.

Application filed February 2, 1909. Serial No. 475,650.

To all whom it may concern:

Be it known that I, ALEXANDER M. MESTON, a citizen of the United States, residing at Roseville, in the county of Placer and 5 State of California, have invented certain new and useful Improvements in Skirt-Markers, of which the following is a specification.

My invention relates to improvements in 10 skirt markers, and the primary object thereof is to secure a quick, more accurate and convenient method for determining the length of ladies' skirts, by marking the same adjacent the bottom.

Another object contemplated by the invention is the provision of means for obtaining 15 a rapid and thorough adjustment of the parts, and more especially the crayon carrier and the rod upon which said device is mounted, thus obviating the manipulation of 20 set screws and other equivalent adjustment securing means.

To the accomplishment of the recited object and others coördinate therewith, the 25 preferred embodiment of the invention resides in that construction and arrangement of parts hereinafter described, illustrated in the accompanying drawings and embraced within the scope of the appended claim.

In said drawings:—Figure 1 is an elevation 30 of the device embodying my invention a portion thereof being shown in sections. Fig. 2 is a bottom plan view of the stool and legs therefor, and Fig. 3 is a bottom view of the 35 stool with the legs removed, and Fig. 4 is a sectional elevation of the locking or securing device.

Similar reference characters designate corresponding parts throughout the several 40 views.

Referring more particularly to the drawings for a detailed description of my invention, the numeral 5 designates a circular stool top constructed preferably of wood and having 45 fastened thereto by means of the screws 6 a trio of arms 7 arranged at angles of approximately 120 degrees. Depending from the junction of the arms 7 is a comparatively short shaft 8 and a rabbeted extension thereof 50 9, which latter is designed to be seated in a suitable bore 10 formed in the central part 11 of the legs 12, provision being made for the vertical adjustment of the top 5 by the employment of a thumbscrew 13, as clearly exhibited in Fig. 2 of the accompanying drawings. It will be noted in this connection

that the upper larger portion of the shaft 8 has its lower terminal resting in a corresponding depression 14 of the portion 11.

In conjunction with the aforesaid device, 60 and as necessary adjuncts thereto I utilize means for adjusting the marker in both vertical and horizontal planes. This result is attained by the use of a rod 15 terminally enlarged as at 16 and having an extremal collar 17 loosely mounted on the shaft 8 and disposed to permit a rotative movement of the rod 15 relative to said shaft. Disposed at right angles with respect to the rod 15 and extending vertically therefrom is a second 65 rod 18 upon which is mounted the marking mechanism. This mechanism comprises in its construction and arrangement a head 19 equipped with a longitudinally extending passage 20 and hollowed or cut out as at 21 70 to serve as a space for the lever 22 having a button 23 on its upper terminal and a block 24 with an outer serrated face 25 on its lower terminal, the said lever 22 being fulcrumed intermediate said terminals and obviously at 75 80 its lower proximal end by the pin 26. In order to give the desired tension to the lever 22 I seat a coil spring 27 beneath the upper terminal thereof and within the space 21. Arranged medially of the head 19 and ex- 85 tends laterally therefrom is an arm 28 provided with spring clips 29 for holding the crayon 30. A similar locking mechanism is inclosed within the lower head portion 31 of the vertically extending rod 18. 90

In practical use the rod 18 is adjusted along the rod 15 and then the head 19 carrying the crayon 30 is placed at the desired height, when the said rod 15 is free to rotate about the skirt as has been hereinbefore set 95 forth. By employing this novel form of frictional locking means very little time is required in obtaining the necessary adjustment of the marker to the rod 18. As will appear manifest it is simply necessary to depress the button 23 and release the block 24 from engagement with the bar 18 or 15, as the case may be, and move the head longitudinally of the bar until the desired position is attained, when pressure on said button is released. 100 105

It should be understood that in its broader aspect the invention comprehends the employment not only of the various means described, but of equivalent means for performing the recited functions. While the 110 arrangement shown is thought, at the present time, to be preferable, it is desired to re-

serve the right to effect such modifications and variations thereof as may come fairly within the scope of the appended claim.

Having thus described the invention, what is claimed as new, is:—

In a skirt marker, the combination of a vertically adjustable stool, a horizontally disposed rod rotatably mounted on said stool, a vertically arranged crayon holder, a spring-pressed frictional locking means carried by said last mentioned rod, and similar means carrying said crayon holder, the said means respectively permitting an adjustment of said vertically arranged rod with respect to said horizontally arranged rod, and said marker relative to the vertically disposed rod, each of said means comprising a head mounted for slidable movement on one of

said rods, each head having a housing formed therein, each of said housings having an opening on opposite sides and at opposite ends thereof, a lever fulcrumed at its proximal end within said casing, means carried by one terminal of said lever and extending through one of said openings for frictionally engaging said rod, and a spring seated within said housing and adapted to normally force the other terminal of said lever outwardly through the other opening.

In testimony whereof I hereunto affix my signature in presence of two witnesses.

ALEXANDER M. MESTON.
